United States Patent Office

Des. 187,639

Patented Apr. 12, 1960

187,639

KITCHEN MAT OR SIMILAR ARTICLE

William D. Timmons, Coshocton, Ohio

Application December 31, 1957, Serial No. 49,075

Term of patent 14 years

(Cl. D9—6)

Fig. 1 is a top plan view of a kitchen mat or similar article, showing my new design.

Fig. 2 is an edge view thereof.

Fig. 3 is a bottom plan view thereof.

I claim:

The ornamental design for a kitchen mat or similar article, as shown.
